APPARATUS FOR DRYING WEBS OF PAPER
REGENERATED FROM CELLULOSE DERIV-
ATIVES

Ernest Bleibler, Ghent, Belgium

Application March 10, 1938, Serial No. 195,049
In Belgium March 11, 1937

7 Claims. (Cl. 34—60)

The invention relates to apparatus for drying webs, foils, sheets, films, bands, strips, pellicles, or the like of paper, preferably transparent paper regenerated from aqueous solutions of cellulose derivatives such as viscose, cuprammonium cellulose, or others. In the following specification and claims all of these goods are shortly designated as webs. Drying of such webs is a highly delicate process requiring continued attention in view of the sensitivity of the web against mechanical damage and in view of the fact that the dried end-product should contain a certain and limited amount of humidity in order to preserve its elasticity and to avoid brittleness and tackiness which might cause foils or sheets lying adjacent to each other to adhere one to the other during their storage.

It is a first object of this invention to arrange the drying apparatus to allow the operator full access to, and survey of the upper surface of the web while it is being fed along and through the drying apparatus, unrestricted by any drying or ventilation chamber or its structural parts. This object in mind, according to this invention, a ventilation chamber is arranged which is exclusively arranged within the space underneath the heated rollers of a roller train which train supports and feeds the web along and through the drying apparatus, the web thus forming a ceiling of, and a closure to that ventilation chamber.

It is another object of this invention to render the operation of the drying apparatus highly efficient and economic in respect of heat consumption by allowing the web to leave the roller train at a degree of inherent moisture which excludes any liability of the web to getting brittle, tacky or sticky, or unsightly.

It is a further object of this invention to conduct the drying process with a view to first fully drying the web and then remoistening it during one and the same procedure and travel through and along the drying apparatus, thus obviating the necessity of separate processes for drying the web and then re-introducing the desired degree of moisture.

A still further object of this invention is to arrange supply, withdrawal, and circulation of the ventilating air within the ventilation chamber and from below the web so as to result in a drying apparatus of highly favorable mechanical, thermal, and economical conditions by supplying fresh air from both sides to the drying apparatus, one part being supplied at the entry of the web into the apparatus, the other part at or near the zone of remoistening.

According to an embodiment of this invention remoistening is effected by conducting or diverting to the remoistening zone from below and within said chamber vapor saturated air from the region of highest vapor saturation of the ventilating air within the chamber.

Another object of this invention is to avoid escaping of ventilation air from the ventilation chamber to the outside above the apparatus and especially to the working room which would mean wasting of heat energy by dissipation into the working room. It is, moreover, an object of the invention to restrict the path of the ventilating air to the space underneath the web thus saving heat and drive energy of the ventilating air by reducing its way and its resistance and to draw ambient air into the ventilating chamber through gaps between the roller train and its supporting side frames, thus blocking the escape of hot and humid air to the outside and especially to the working and surveying place of the operator and thus reducing to a great extent the inconvenience and the strain of his work.

Further objects of the invention will appear from the following description and the drawings affixed thereto.

In the drawings affixed to my specification and forming part thereof, an embodiment of my invention is illustrated by way of example. It will be readily understood however, that my invention is by no means limited to this construction and that the scope of my invention and the ambit of my appended claims extend to any construction incorporating the broad principle underlying my invention.

In the drawings:

Fig. 1 shows a longitudinal elevation, partly in section, of a drying apparatus constructed in accordance with my invention,

Fig. 2 is a plan view of a ventilation chamber, and

Fig. 3 is a vertical cross-section, in an enlarged scale, along line 3—3 of Figs. 1 and 2.

Fig. 4 is a vertical section along line 4—4 of Fig. 5, and

Fig. 5 is a longitudinal section along line 5—5 of Fig. 4 on an enlarged scale of the heat recuperator of Figs. 1 and 2.

Referring to the drawings, 11, 12 is a roller train composed of an upper tier or rollers 11 and a lower tier of rollers 12 supported by side frames 26, 27, which may be covered or coated by insulating material as indicated at 30 and 31. The rollers 11, 12 support and feed the web 13 to be dried through and along the roller train. The rollers

may be heated by hot air, steam, hot water, or other liquid or medium, by supplying the heating medium, by means of pipes 14, to the hollow interior of the rollers at one side and withdrawing the medium at the other side through pipes 15, or vice versa. The rollers may be driven in any suitable manner, for instance by gearing 16, 17, or by the forward motion of the material to be dried. The web 13 is fed to the rollers of the roller train at the entry side 21 by means of the feed rollers 20 and is delivered to the wind-up reel 23 at the exit end 22 of the web. The ventilation chamber 25 is confined to the space underneath the rollers 11, 12 and web 13, and is enclosed between the side frames 26, 27 on the one hand, and between the rollers or web and the floor or base structure 28 on the other hand.

Two ventilating systems are allotted to the ventilation chamber, each consisting of a ventilator and air-ducts. Fresh air is supplied by ventilator 33, which may be driven by electromotor 34. The air is conducted through channel 35 arranged, parallel to and below the ventilation chamber, within the floor. Channel 35 opens at 36 and 37 to the ventilation chamber 25, the openings being controlled by adjustable valves or flaps 38. The discharging ventilating system consists of ventilator 40, driven by electromotor 41, and the exhaust channel 42 extending within channel 35 and opening at 43 and 44 into the ventilation chamber; the openings 43 and 44 being likewise controllable by means of adjustable flaps 45. The wall of channel 42 is of heat conductive material so that fresh air, entering channel 35, may be preheated by the heat of the discharged air, and transferred to it through the heat conductive wall of channel 42. The exhaust air is discharged by means of ventilator 40 into the open air through chimney 46. Supplemental ducts 49, 50 are arranged opening into the ventilation chamber at 51, 53 and 52, 54 respectively. The passage through these openings may be controlled by means of valves or flaps 55, which may be arranged at 53, 54 for instance.

The chamber is sub-divided into sections 61, 62, 63, 64, 65, 66, each section being provided with air conveyors or fans 67 and nozzle 72; and the fans may be driven by any convenient drive as indicated at 68. The nozzles 72 are provided with guiding surfaces 73 and jet slots 74 in their upper surface. A heat recuperator may be arranged within both conduits 35, 42 in addition to the heat recuperating arrangement of ducts 35 and 42 for interchanging heat between both conduits and for recovering the heat which may be finally contained within the air to be discharged.

The heat recuperator 71 may be of any conventional type and is shown in Figs. 4 and 5 on an enlarged scale.

A group of parallel sheets 80 of heat conducting material, for instance of metal, is arranged within the duct 35. The sheets are spaced from each other by means of alternately arranged vertical spacing bars 81 and horizontal spacing bars 82. These sets of spacing bars thus form groups of horizontal ducts 83 and of vertical ducts 84, the one kind of ducts being imbedded between the ducts of the other kind. The vertical ducts 84 are inserted into, and connected with duct 35, whereas the horizontal ducts 83 are inserted into, and connected with duct 42.

The supply current of fresh ventilating air and the discharge current of moist air thus cross each other in the form of relatively thin layers separated by thin heat conducting sheets only so that

heat will be easily and effectively exchanged between both currents. The recuperator may be provided with a separator or trap for assembling the condensed water, not shown in the drawings.

5 The operation of the apparatus is as follows:

The wet web 13 issuing from the baths or tanks and entering at 21 is conveyed through the roller train and finally wound up on reel 23 at the end 22 of the roller train. The air within the chamber is circulated in each section by means of fans 67, passes through the jets 74, sweeps the lower surface of the web, and is then drawn back at the sides to and by the fans 67, as indicated by the arrows in Fig. 3. The air sweeping the web 15 will take up the heat and the vapor emanating from the web. The air within the ventilation chamber will thus become more and more saturated with vapor until, as is known, a maximum of saturation will be reached at a place lying between about a third and a half of the length of the roller train or air chamber respectively. At that place, which may be at opening 43, the saturated air is discharged by means of ducts 42 and ventilator 40, and the remainder of the saturated air will be withdrawn through opening 44. Fresh air for replacing the withdrawn saturated air is admitted at the entry side of ventilation chamber 25 through opening 36 and may be additionally supplied at the last section or sections of the roller train at 31, from which point fresh air will flow to either side of the air chamber as indicated by the arrows in Fig. 1. Other parts of fresh air may enter the ventilation chamber together with the web and at the end of the ventilation chamber where the web leaves the roller train.

Now, experience shows that the goods which preferably come into consideration for the apparatus according to this invention, namely transparent cellulosic papers regenerated from viscose or other aqueous solutions of cellulose derivatives, when immediately dried to their desired contents of humidity, will be tacky or sticky and will tend to adhere one to the other; when web or sheet surfaces are contacting one another. Besides, it 45 will be difficult to control the drying process so as to be interrupted just at the point where the desired degree of humidity is reached.

A better result has been obtained by fully drying the cellulose paper and to store it in an air-conditioned storage room. The humidity and temperature of this room may then be controlled, so that the foils will retake the humidity which had been removed in excess of the desired amount. This operation may be easily controlled and the 55 tendency of the foils to adhere one to the other will be greatly reduced; a draw-back of this procedure being however the long time, some days or even some weeks, which it necessitates. If the goods are needed immediately after having been produced, they will be brittle and will give cause to disturbances when being cut or otherwise handled.

When trying to remoisten the web by direct supply of water vapor, other drawbacks are 60 encountered with, as the web avidly resorbs the water and thus the procedure cannot be controlled and moreover, this manner of restoring humidity to the film is disastrous in view of heat economy.

These drawbacks are fully eliminated by applying the system as will now be described.

In order to produce, under economical conditions regarding the heat applied to the system, a web which leaves the drying apparatus with the desired degree of humidity without being tacky

on the one hand and brittle on the other hand, the web is first completely dried and then remoistened from below during one and the same process during its uninterrupted travel through and along one and the same drying apparatus and above the same drying chamber.

To this end, a current of saturated air which has been diverted downwards from the zone of high or highest saturation in the ventilation chamber is supplied from below to the last section or sections of this chamber and is used for remoistening the web during its travel through the last section or sections of the ventilation chamber.

In order to remove the great quantity of water which is to be evaporated from the web, a great quantity of air is used which is to be saturated by the vapor emanating from the web, and to be heated, through the intermediary of the web, by the rollers, as high as possible, and which is then withdrawn. This air before being withdrawn is highly appropriate for remoistening the web which had formerly been completely dried. This highly saturated air will react readily and may thus be used in the same apparatus so that the disadvantages will be avoided otherwise resulting from difficulty of control and deficiency of heat economy when introducing water vapor directly.

In the embodiment illustrated in the drawings, the last roller train section 66 is used for the purpose of remoistening the web. Highly saturated air from the zone of high air saturation is drawn to the last section 66, by means of the fans 67 of this section, through the ducts 49, 50 and openings 51, 53 and 52, 54 respectively. The passage through the ducts and thus the degree of remoistening may be controlled by means of the above mentioned flaps 55. The remoistening air is admixed to the air circulated within section 66.

Volume, pressure, and velocity of supply and discharge air currents may be controlled by controlling the working conditions of the ventilators 33 and 40 and the adjustment of the flaps 38 and 45 respectively.

In a preferred embodiment of the invention these controlling means will be regulated so as to establish within the ventilation chamber a small depression with regard to the ambient air and thus to avoid heat losses by discharge of the ventilation air to the outside through the gaps 80, 81 between the ends of the rollers 11, 12 of the roller train and the side frames 26, 27 respectively; to allow, moreover, the ambient air to be drawn through gaps 80, 81 into the ventilation chamber. As heat and vapor are withdrawn from the lower surface of the web, the space above the rollers will be substantially free from any emanating heat and vapor and the convenience and supervision of operation will be increased to a considerable extent, the more as the space above the rollers is readily accessible due to the avoidance of any structural parts of the ventilation chamber which, according to this invention, has been confined to the space underneath the roller train.

I claim:

1. An apparatus for drying webs of paper regenerated from aqueous solutions of cellulose derivatives, including a base structure, side frames on said base structure, a roller train supported by said side frames, said roller train for supporting and feeding the web through and along said apparatus; a ventilation chamber arranged exclusively below said web and within the space enclosed by said roller train, said side

frames and said base structure; means for generating a current of fresh ventilating air within and longitudinally of said chamber, means for withdrawing the moist ventilating air from said chamber, a duct connected with said means for producing fresh ventilating air, a duct connected with said means for withdrawing the moist ventilating air, said ventilating chamber having at least one inlet from said first named duct and at least one outlet into said last named duct; both said ducts being arranged underneath said ventilation chamber within said base structure and opening from underneath into said ventilating chamber by means of said inlet and said outlet respectively; at least one air mover and a nozzle both being located within said chamber between said inlet and said outlet for circulating said ventilating air within said chamber and directing it to sweep over the lower surface of said web.

2. An apparatus for drying webs of paper regenerated from an aqueous solution of cellulose derivatives, including a base structure, side frames on said base structure, a roller train supported by said side frames, said roller train for supporting and feeding the web through and along said apparatus; a ventilation chamber arranged exclusively below said web and within the space enclosed by said roller train, said side frames and said base structure; a ventilating air generating device for generating a current of ventilating air within and longitudinally of said ventilating chamber, and a ventilating air distributing device for circulating said current of ventilating air within and transversely of said ventilating chamber and for directing ventilating air to sweep over the lower surface of said web; said ventilating air generating device including means for producing a current of fresh ventilating air, means for discharging the moist ventilating air from said chamber, said ventilating chamber having at least one inlet and one outlet spaced a substantial distance apart from each other, ducts connecting both said means, respectively, to said inlet and said outlet of said ventilating chamber; said ventilating air distributing device including at least one fan and one nozzle both within said chamber.

3. An apparatus for drying webs of paper regenerated from aqueous solutions of cellulose derivatives, including a base structure, side frames on said base structure, a roller train supported by said side frames, said roller train for supporting and feeding the web through and along said apparatus; a ventilation chamber arranged exclusively below said web and within the space enclosed by said roller train, said side frames and said base structure; a ventilating air generating device, said chamber having at least one inlet and one outlet spaced at a substantial distance from said inlet; said ventilating air generating device including means for producing a current of fresh ventilating air longitudinally of said chamber between said inlet and said outlet, means for discharging the moist ventilating air from said chamber, ducts connecting said inlet of said ventilating chamber to said means for producing a current of fresh ventilating air and said outlet to said means for discharging the moist ventilating air, respectively, both said ducts being arranged underneath said roller train; a series of air movers and nozzles being provided in, and spaced longitudinally of, said chamber for directing air of said current of ventilating air to sweep over and transversely of the lower surface of said web.

4. An apparatus as set forth in claim 3, where-
in said ducts are arranged parallel to, and un-
derneath, the ventilation chamber, co-axially,
one within the other and separated from one
another by a wall of heat conductive material.

5. An apparatus for drying webs of paper re-
generated from aqueous solutions of cellulose de-
rivatives, including a base structure, side frames
on said base structure, a roller train supported
by said side frames, said roller train for sup-
porting and feeding the web through and along
said apparatus; a ventilation chamber arranged
exclusively below said web and within the space
enclosed by said roller train, said side frames
and said base structure; said chamber having
at least one inlet and one outlet spaced at a
substantial distance from said inlet; a ventilat-
ing air generating device; said ventilating air
generating device including means for producing
a current of fresh ventilating air longitudinally
of said chamber between said inlet and said out-
let, means for discharging the moist ventilating
air from said chamber, a fresh air duct and a
discharge air duct respectively connecting said
inlet of said ventilating chamber to said means
for producing a current of fresh ventilating air
and said outlet to said means for discharging
the moist ventilating air, both said ducts being
arranged underneath said roller train; a series
of air movers and nozzles being provided in, and
spaced longitudinally of, said chamber for direct-
ing air of said longitudinal current of ventilat-
ing air to sweep over and transversely of the
lower surface of said web, and means for supply-
ing humid air to said web at a place located
near the discharge end of said chamber and
from below said chamber for remoistening said
web; said fresh air duct having an additional
opening into said chamber at said web remois-
tening place.

6. An apparatus for drying webs of paper re-
generated from aqueous solutions of cellulose de-
rivatives, including a base structure, side frames
on said base structure, a roller train supported
by said side frames, said roller train for sup-
porting and feeding the web through and along
said apparatus; a ventilation chamber arranged
exclusively below said web and within the space
enclosed by said roller train, said side frames
and said base structure; said chamber having
at least one inlet and one outlet spaced at a
substantial distance from said inlet, a ventilat-
ing air generating device; said ventilating air
generating device including means for producing
a current of fresh ventilating air longitudinally
of said chamber between said inlet and said out-
let, means for discharging the moist ventilating
air from said chamber, a fresh air duct and a
discharge air duct respectively connecting said
inlet of said ventilating chamber to said means
for producing a current of fresh ventilating air
and said outlet to said means for discharging
the moist ventilating air, both said ducts being
arranged underneath said roller train; a series

of air movers and nozzles being provided in, and
spaced longitudinally of, said chamber for di-
recting air of said longitudinal current of ven-
tilating air to sweep over and transversely of
the lower surface of said web; said apparatus
further including a remoistening conduit ar-
ranged underneath said roller train and said
web, said conduit having two openings leading
into said ventilation chamber, one of said open-
ings arranged at one third to one half the cham-
ber length calculated from the web entry side
of said ventilation chamber, for giving admis-
tance to a part of vapor saturated air from said
chamber to said conduit, the other of said open-
ings being arranged at a place located near the
discharge end of said chamber and adapted to
redirect said part of vapor saturated air into
said chamber for remoistening said web; said
fresh air duct having an additional opening com-
municating with said ventilation chamber at a
place in the vicinity of said saturated air redi-
recting opening of said remoistening conduit.

7. An apparatus for drying webs of paper re-
generated from aqueous solutions of cellulose de-
rivatives, including a base structure, side frames
on said base structure, a roller train supported
by said side frames, said roller train for sup-
porting and feeding the web through and along
said apparatus; a ventilation chamber arranged
exclusively below said web and within the space
enclosed by said roller train, said side frames
and said base structure; said chamber having
at least one inlet and one outlet spaced at a sub-
stantial distance from said inlet; a ventilat-
ing air generating device; said ventilating air gen-
erating device including means for producing a
current of fresh ventilating air longitudinally of
said chamber between said inlet and said outlet,
means for discharging the moist ventilating air
from said chamber, a fresh air duct and a dis-
charge air duct respectively connecting said inlet
of said ventilating chamber to said means for
producing a current of fresh ventilating air and
said outlet to said means for discharging the
moist ventilating air; both said ducts being ar-
ranged underneath said roller train; a series of
air movers and nozzles being provided in, and
spaced longitudinally of, said chamber for di-
recting air of said longitudinal current of ven-
tilating air to sweep over and transversely of
the lower surface of said web, said apparatus
further including a remoistening conduit com-
municating with said ventilation chamber at a
place at about one third to one half the chamber
length calculated from the web entry side of
said chamber and opening into said chamber
at a place located near the discharge end of
said chamber, said remoistening conduit and said
fresh air and discharge air ducts being arranged
parallel to the length direction of said ventila-
tion chamber and underneath the floor of said
chamber.

ERNEST BLEIBLER.
